UNITED STATES PATENT OFFICE.

FRANK YOKEL, OF AVALON, PENNSYLVANIA.

DESIGN FOR A LAMP SHADE.

Application filed May 22, 1922. Serial No. 2,353. Term of patent 7 years.

To all whom it may concern:

Be it known that I, FRANK YOKEL, a citizen of the United States, residing at Avalon, in the county of Allegheny and State of Pennsylvania, have invented a new, original, and ornamental Design for Lamp Shades, of which the following is a specification, reference being had to the accompanying drawing, forming part thereof.

The figure is a view in perspective of the lamp shade, showing my new design.

I claim:

The ornamental design for a lamp shade, as shown.

FRANK YOKEL.
